UNITED STATES PATENT OFFICE.

JOHN F. DONNELLY, OF BROCKTON, MASSACHUSETTS, ASSIGNOR TO PANCO RUBBER COMPANY, OF CHELSEA, MASSACHUSETTS, A CORPORATION OF MASSACHUSETTS.

TAP-SPLITTING MACHINE.

Application filed March 3, 1925. Serial No. 12,978.

To all whom it may concern:

Be it known that I, JOHN F. DONNELLY, a citizen of the United States, residing at Brockton, in the county of Plymouth and 5 State of Massachusetts, have invented certain new and useful Improvements in Tap-Splitting Machines; and I do hereby declare the following to be a full, clear, and exact description of the invention, such as will enable others skilled in the art to which it 10 pertains to make and use the same.

The present invention relates to an improvement in tap splitting machines.

The object of the invention is to produce 15 a machine for splitting a tap sheet blank of rubber compound transversely of the shank of the tap, parallel to the opposite surfaces thereof, for the purpose of inserting a piece of reinforcing material before the tap is 20 vulcanized. The invention consists in the machine hereinafter described and particularly defined in the claims.

In the accompanying drawings illustrating 25 the preferred form of the invention, Fig. 1 is a front elevation; Fig. 2 is a transverse sectional elevation; Fig. 3 is a plan; and Fig. 4 is a detail hereinafter referred to.

The illustrated embodiment of the invention is described as follows: The knife K is 30 a disk knife supported to rotate on a vertical axis. The tap blanks T are fed edgewise to the knife by feeding means, which presents the edge of the tap blank to the edge of the knife in proper position to permit the knife 35 to slit the shank edge of the tap blank. Suitable gauges are provided to assist the operator in the presentation of the blanks to the machine.

In detail the construction is as follows: 40 The machine is provided with a suitable bed 10, adapted to stand on a table. This bed 10 carries all the various parts of the machine. The knife K is mounted on a knife shaft 11, which is received in a bearing bushing 12, 45 screw-threaded exteriorly and received in a threaded opening in the knife carrier frame 13. The shaft is provided with a fixed collar 14, which bears against the washer 15, which, in turn, engages the lower end of the bearing sleeve 12. The upper end of the bearing sleeve 12 is provided with a spanner collar 16, by means of which the bearing sleeve 12 may be adjusted vertically in the frame 13, and when the correct adjustment 50 is secured the clamp bolt 17 is screwed up 55 and the bearing sleeve is held in fixed position. Threaded on the knife shaft are two spanner collars 18, the lower one of which engages the washer 19, which in turn engages the upper surface of the bearing sleeve 60 12. The collars 18 may be adjusted to hold the knife shaft in fixed vertical position. The knife shaft 11 is also provided with a pulley 20, and the frame 13 is provided with an additional bearing 21 on the upper end 65 of the knife shaft. The frame 13 is provided with a bearing bracket 22, which carries a shaft 23, which, upon its ends, has two pulleys 24. A belt running from a suitable shaft or motor descends to one of the pulleys 24, passes around it, takes a quarter turn, thence passes around the knife pulley 20, and back to the other pulley 24, and thence to the source of power for driving 70 the knife.

The knife frame 13 is mounted on the knife frame base 25, being secured thereto by four bolts 26. The knife frame base 25 is supported upon four bosses 27, which are carried by a frame 28 square in horizontal 75 cross-section, secured to the base 10 by means of bolts 30. Four cap bolts 31 are employed to secure the knife frame base to these bosses 27. This affords a rigid support for the knife frame base on the base 10 of the machine.

The frame 28 has a bracket boss 32 on its front side, to which the bracket 33 is bolted by means of the bolts 34. To this bracket 33 is secured the travelling belt support 35, upon which the belt B rests. The 80 belt B is carried by two pulleys 36 and 37. The pulley 37 is mounted on a shaft 38 carried by the pillow-blocks 39 and 40 bolted to the base 10 of the machine. The pulley 36 is 85 mounted on the shaft 41 carried by the pillow-blocks 42 and 43. These pillow-blocks are adapted to be adjusted longitudinally of the belt in order to keep the belt taut; thus, adjusting screws 44 adjust the position of the pillow-block 42, and adjusting screws 45 90 adjust the position of the pillow-block 43. Securing bolts 46 and 47 are employed to secure the pillow-blocks after they have been 95 adjusted to the correct position. The shaft 38 carries the sprocket wheel 49, which is 100 connected by means of the sprocket chain 50 to the sprocket wheel 51 on the shaft 52, supported in the pillow-block 53. This shaft 52 carries a gear 54 which meshes with a pinion 55 mounted on the shaft 56 supported 105 110

in the bearings in the pillow-block 57, and such shaft 56 also carries the tight and loose pulleys 58, by which the feeding means of the machine are driven.

- 5 The taps are fed by belt and roll feeding means described as follows: The belt B is an important element of the feeding means already referred to, and it moves in the direction of the arrow 59, shown in Fig. 1, 10 over the belt supporting table 35, and upon the belt are carried the tap blanks T to the knife. At the entering end of the table 35 the tap is directly supported by a bottom feed roll 60, mounted on the shaft 61 supported in a front bearing in a bracket 62 and rear bearings in the frame 28. This roll 60 is provided with short projecting pins engaging the tap blank on the under side, and it is rotated by power, as hereinbefore described, to contribute to the feeding of the tap blanks to the knife. Above the feed roll 61 is located one of the top feed rolls 63, which is mounted on a shaft 64. This shaft 64 is supported in bearings in a 25 feed roll carrying plate 65. This plate is shown in plan in Fig. 3. Its corners are notched, as shown, so that the plate is received between the four posts 27, which rise from the webs 28 and 29. The outboard 30 end of the shaft 64 is received in a hole in the lower end of the outboard bearing carrier 66, the shank of which is carried in a bracket 67, secured to the frame 13. A set screw 68 secures the part in adjusted position in the bracket 67.

The feed roll carrying plate 65 is held from lateral movements by direct engagement with the post 27 above referred to. These posts 27 are provided with set screws 40 69, which take against surfaces of the plate, by which the plate may be moved longitudinally in order to bring it in correct position with relation to the knife K. The plate 65 is adjusted vertically by means of eight adjusting screws 70, two above and two below each end of the plate, as shown clearly in Figs. 1 and 3. By loosening the set screw 68 holding the outboard bearing carrier 66, the feed roll carrying plate may be adjusted vertically to correct position with relation to the knife. If necessary, the set screws 69 may be loosened to facilitate this adjustment. The plate 65 carries rearward bosses 71 and 72, which are provided with 55 holes to form bearings to receive the feed roll drive shaft 73. This drive shaft is provided with bevel gears 74, 75 and 76, which mesh with bevel gears 77, 78 and 79. The bevel gear 77 is on the rear end of the drive shaft 64, and through it power is applied to the feed roll 63. A sprocket shaft 80 is mounted in a bearing in the boss 72 and a bearing in the plate itself. This is connected by bevel gears 81 and 82 with the 60 shaft 73. On the rear end of the shaft 80

is a sprocket wheel 83, from which a sprocket chain 84 runs to the sprocket wheel 85 on the shaft 52, and by this means power is transmitted to the feed shaft 73 without interfering with the capacity of vertical adjustment of the feed plate 65. Two additional feed rolls are provided, located parallel to and in the same plane with the top feed roll 63. These feed rolls 86 and 87 are supported upon shafts 88 and 89, respectively, carried in the bearings in the feed plate 65 parallel to the shaft 64. The rear ends of these shafts 88 and 89 carry the bevel gears 78 and 79 heretofore referred to, and the shaft 73 is thereby connected with them to drive these feed rolls.

The first top feed roll shaft 64, and the single bottom feed roll shaft 61, are provided with intermeshing gears 96 and 97, by which the top shaft 64 drives the lower shaft 61.

The relations of the several top feed rolls 63, 86 and 87, to the belt B and the bottom feed roll 60, and of all of these to the knife K and the table 35, are well illustrated in Fig. 4, which shows the several rolls in cross-section, and the knife as separate from the knife shaft upon which it is carried.

The feed roll carrier 65 is provided on the left hand side of the feed roll 63 with a guard plate 90, secured to the bracket 91, in turn mounted on the feed plate, as shown in Fig. 3. This guard plate protects the hand of the operator from accidental engagement with the feed roll 63. A gauge 92 has a vertical member against which the shank edge of the blank is adapted to be placed in order to correctly position the tap blank for presentation to the rolls. This gauge 92 has a horizontal foot provided with slots and screws 93, which pass through these slots and screw into a plate 94, so as to secure the gauge in place on the plate. The level of this plate is a little below the level of the top of the belt B, and it is supported on an ear 95 which is cast integral with the pedestal or bracket 62.

The operation of the machine is as follows: The two power belts by which the machine is driven are set in motion, and thereby the feed belt and feed rolls are actuated and the knife K is caused to rotate. The operator takes a tap blank T and places it on top of the belt, with its shank edge against the gauge 92, and presses it gently upon the belt B, which thereby carries it in between the top feed roll 63 and the belt B, which thereby feed the tap along to the right, as shown in Fig. 3. The shank portion of the tap is presently gripped between the top feed roll 63 and the bottom feed roll 60, so that the shank portion of the tap is steadied and supported by these two rolls at the same time that the tap is being fed through the machine between the travelling

belt B and the feed roll 63. The feed rolls 86 and 87 cooperate with the belt to carry the tap blank along through the machine. Taps, the shanks of which have been split 5 by the machine, are discharged from the end of the belt B at the right hand end of the machine.

Having thus described the invention, what is claimed is:

10. 1. A tap splitting machine having a disk knife and means for rotating it, tap feeding means comprising a travelling belt, and a feed roll pressing the tap against the belt to carry the tap past the knife.
  15. 2. A tap splitting machine having, in combination, a knife, means for driving it, a feed belt, a top feed roll located above the belt and extending beyond it, and a bottom feed roll extending from the edge of the 20 belt to the end of the top feed roll, said knife entering the space between the top and bottom feed rolls and acting, as the tap is fed in between the top feed roll on the one side, and the belt and bottom feed roll 25 on the other side, to split the shank portion of the tap transversely.
  30. 3. A tap splitting machine having, in combination, a knife, means for rotating it, a table, a feed belt on the table, a plurality of top feed rolls cooperating with the feed belt to grip the tap to feed it to the knife, the first feed roll being longer than the others and extending beyond the edge of the belt, and a bottom feed roll extending from 35 the edge of the belt to the end of the first top feed roll, and cooperating with each
- other correctly to present the shank of the tap to the knife.
4. A tap splitting machine having, in combination, a knife, tap feeding means 40 comprising a table, a feed belt resting on the table, a plurality of top feed rolls supported in a feed roll carrying plate, the feed rolls and belt cooperating to feed the tap blank to the knife, means for holding the feed roll carrying plate in position comprising stationary posts and means for adjusting the feed roll plate vertically, feed roll driving means comprising a feed roll drive shaft mounted on the plate, bevel 45 gears connecting the shaft with the rolls, and sprocket gearing for driving the feed roll driving shaft, thereby permitting vertical movement of the plate without impairment of the power drive connections. 50
  5. A tap splitting machine having, in combination, a base, a frame supported on the base, a knife carrying frame provided with a bearing for a vertical knife shaft, a knife shaft mounted in said bearing, a disk knife carried by the knife shaft, feeding means for feeding taps to the knife comprising a short roll and a travelling belt mounted in fixed position on the frame of the machine, a plurality of feed rolls, a feed roll carrying plate for carrying said feed rolls, having provision for vertical adjustment, and means for actuating the feed rolls and plate to feed the tap blanks to the knife. 55

In testimony whereof I have signed my 70 name to this specification.

JOHN F. DONNELLY.
